SHUTTLE

Luigi Pavia, Allentown, Pa.

Application January 12, 1940, Serial No. 313,532

5 Claims. (Cl. 139—208)

This invention relates to loom shuttles and has for an object to provide an improved construction of spindle, spindle head and associated parts, whereby the spindle is automatically maintained in a central position when fitted into a shuttle body.

Another object of the invention is to provide in a shuttle a spindle having a head pivotally mounted in a box and resilient means for resisting movement from a neutral position and also from an extreme open position.

An additional object of the invention is to provide an improved shuttle structure including a spindle which may be solid or split at the head 15 end, with spring-pressed rounded members for resiliently holding the spindle in a central or neutral position and acting to return the spindle to that position when permitted to do so.

A further object of the invention is to provide 20 a shuttle with a spindle having a spindle head pivotally mounted in a housing which may have bracing feet at one end or jaws for receiving the enlarged head of a quill.

In the accompanying drawing—

25 Fig. 1 is a top plan view of a shuttle provided with a spindle, spindle head, a housing, and associated parts embodying the invention;

Fig. 2 is a sectional view through Fig. 1 approximately on the line 2—2;

30 Fig. 3 is an enlarged top perspective view showing a part of a spindle, spindle head and housing constructed according to the showing in Figs. 1 and 2;

Fig. 4 is an enlarged fragmentary sectional view through Fig. 2 approximately on the line 4—4;

Fig. 5 is a fragmentary sectional view through Fig. 4 approximately on the line 5—5;

Fig. 6 is a view similar to Fig. 5 but showing 40 a slightly modified construction;

Fig. 7 is a view similar to Fig. 6 but showing a second modified construction;

Fig. 8 is a view showing a modified form of the invention, the head and housing of the device being shown in horizontal section;

Fig. 9 is a sectional view through Fig. 8 approximately on the line 9—9;

Fig. 10 is a top plan view of the left hand of the structure shown in Fig. 8, a jaw filling plate being shown in connection therewith;

Fig. 11 is a fragmentary sectional view through Fig. 10 on the line 11—11;

Fig. 12 is a perspective view of the jaw filling plate shown in Fig. 10;

Fig. 13 is a view similar to Fig. 11 but showing

a modified arrangement of the jaw filling plate; and

Fig. 14 is a perspective view of the jaw filling plate shown in Fig. 13.

Referring to the accompanying drawing by numerals, 1 indicates the body of the shuttle which may be a standard shuttle body now in common use on the market. In the shuttles now on the market a quill holder or spindle is provided having a head and means for holding the parts in operative position.

In the present invention there is provided a spindle 2, which may be of any special or standard construction desired. This spindle, at the pivot end, is rigidly connected with a solid spindle head 3, which is chamfered along the line 4 whereby the spindle may be swung upwardly to the dotted position shown in Fig. 2 when loading or unloading the quill. The head 3 is pivotally supported by a bolt 5, which is a standard bolt 10 used in shuttles now on the market. A housing 6, which is U-shaped in cross section as shown in Fig. 5, surrounds the head 3 and is provided with cutaway portions 7 which allow the head to swing downwardly when the spindle swings 15 upwardly. A pair of feet 8 and 9 extend from the front bottom plate, as shown in Figs. 1 and 3. These feet rest in suitable notches provided in the body 1 and prevent any downward tilting of the housing 6. The housing 6 is provided with 20 apertures 10 and 11 on opposite sides, as shown in Fig. 4. These apertures partly accommodate balls 12 and 13, which balls are pressed by coil 25 springs 14 and 15. The respective balls 12 and 13 are movably mounted in comparatively large 30 bores 16 and 17, while the springs 14 and 15 are arranged in smaller bores 18 and 19. The apertures 10 and 11 are of slightly less diameter 35 than the diameter of the balls so that the balls may project therein a desired distance, as for 40 instance, to a point slightly spaced inwardly from the outer surface of the housing. Instead of using balls, cylindrical members 20 having round ends 21 could be used, as shown in Fig. 6. Also, as shown in Fig. 7, cylindrical members 22 may 45 be used having a rounded cone-shaped projection 23. In all forms shown in Figs. 5 to 7 inclusive, an inclined surface is provided so that whenever it is desired to swing the spindle 2 from the position shown in Figs. 1 and 4 upwardly, the balls or similar devices will be swung 50 in an arc away from the respective apertures 10 and 11, the center of the arc being the center of bolt 5. This will cause the respective coil springs 14 and 15 to be compressed and press the balls 55

against the inner surface of the walls of the housing 6. When the spindle is swung upwardly, as shown in Fig. 2, the action of the springs will be to yieldingly hold the spindle in its upper or outward position whereby a quill may be applied or removed whenever desired. However, when the spindle 2 is forced downwardly through the slot 24 in housing 1, the balls 12 and 13 will not move completely out of the apertures 10 and 11 and, consequently, whenever the spindle is released it will quickly move back into its neutral or central position, as shown in Fig. 2. If this spindle is swung upwardly a short distance the same action takes place. From this it will be seen that as the springs 14 and 15 and balls 12 and 13 function, there will be a continuous tendency to hold the spindle 2 in its correct central position in the shuttle body 1 unless the spindle is manually forced to its extreme outer position, as shown in dotted lines in Fig. 2.

In the structure illustrated in Figs. 1 to 7 inclusive, the spindle head 3 is solid, but if desired the structure could be slightly modified, as shown in Figs. 8 to 12, where the spindle 2' has a head 25 divided into sections 3' and 3''. The casing 6' in this form of the invention is provided with jaws 25 so as to receive the enlarged end or head 26 of the quill 27. In case the head or end 26 of the quill should be very thin, there is provided a jaw-filling plate 28, as shown in detail in Fig. 12. This plate is provided with a body 29 having a slot 30 through which a clamping screw 31 extends for clamping the filling plate in any desired adjusted position. A holding or spacing member 32 extends from one end of the body 29 and as shown in Fig. 10 for holding the head 26 against the respective jaws 25 so that there will be no undesirable loose motion. If the head 26 should be a little thicker or appreciably thicker, 40 the filling plate 28 could be moved to the left, as shown in Fig. 10 or could be completely removed.

In all forms of the invention, balls 12 and 13 are used, or round members as shown in Figs. 45 6 and 7, so that the springs acting therein will continually tend to maintain the spindle in a central correct position in respect to the shuttle body 1. In case this spindle should be forced in the wrong direction, namely, through slot 24, the 50 balls and associated parts will quickly move the spindle back to its correct position.

In Figs. 13 and 14 another form of jaw filling plate is disclosed wherein the spacing member 32' is the same as shown in Fig. 12, but the body 55 is provided with rearwardly extending slotted members 33 and 34 for accommodating a threaded member or bolt 35. This form of the invention is particularly desirable where the spindle head 3 is solid as the bolt 35 may extend therethrough 60 and firmly clamp the device in any desired adjusted position.

I claim:

1. In a loom shuttle, a spindle, a head for said spindle, a housing for said head having openings in opposite faces of sufficient size to permit

said spindle to partly swing therethrough, a pin for pivotally connecting said head with said housing, said pin being positioned substantially centrally of the head, a spring pressed member carried by said head on each side of said pin acting 5 against said housing for resiliently resisting swinging movement of said spindle in two directions, said spring pressed member also functioning to yieldingly hold the spindle in an open position and to return said spindle to a central position when moved past said central position a short distance in either of two directions. 10

2. In a shuttle as set forth in claim 1 characterized by forming the housing with laterally extending feet projecting from the bottom of the 15 housing.

3. In a loom shuttle, a spindle, a head carried at one end of said spindle, said head and spindle being split longitudinally from the rear end of the head to a point near the free end of the spindle; 20 a housing for said head provided with a pair of straight spaced parallel perforated side walls, said head being formed with a bore opposite each of the perforations in said side walls, a coil spring in each bore, a member having a 25 rounded portion fitting in each of said perforations, said members being urged by said springs toward said perforations, the respective parts of the head being urged in opposite directions against said perforated walls to frictionally hold 30 the spindle in various adjusted positions when said spring pressed members are out of the perforations in said walls and a retaining bolt extending through said head and housing between said springs for pivotally mounting the head so 35 that it may be automatically centered by said springs and said members having rounded portions.

4. A device as set forth in claim 3 characterized by the use of spherical balls fitting each of 40 the perforations in the side walls.

5. In a shuttle, a spindle and a head, a housing for said head, said housing being formed with a pair of facing jaws, a filling plate having an apertured portion positioned on said spindle and partly filling said jaws, said filling plate having a slotted body fitting over part of said head, a threaded member extending through the slot in said body for adjustably locking said filling plate in functioning position, a member extending through said housing and said head substantially centrally thereof, said head being provided with a pair of bores near the respective ends extending from one side of the head to near the other side, one bore being on each side 55 of said member, one of said bores opening on one side and the other on the other side, a ball in each of said bores, said housing being provided with an aperture in line with each of said bores, said apertures being of less diameter than said bores and a coil spring in each of said bores for urging 60 said balls as far as possible into said apertures for resiliently locking said head to said housing and returning the head to a central position.
